UNITED STATES PATENT OFFICE.

HOWARD E. MARSH, OF LOMPOC, CALIFORNIA.

TUNNELING MACHINE.

Application filed October 7, 1924. Serial No. 742,122.

In the mining or cutting of kieselguhr or other diatomaceous earth, it has been the practice to remove the overburden from the natural deposit until the upper surface of 5 the topmost stratum of kieselguhr or earth desired is exposed, and then methods and apparatus are employed for cutting through the same inwardly from its face to obtain the material in the condition desired. This 10 present practiced method of obtaining the material necessitates the incurring of heavy expense in the removing of the overburden from each succeeding stratum as successive strata of the desired material are removed. 15 Locations for receiving the removed overburden are necessary, and if they are distant from the deposit the removal and disposal of the overburden is costly. Valuable cut material is wasted in dust and fines under 20 present methods, and it is to overcome the loss in handling the overburden and the waste of the material that I have designed the following invention.

My present invention relates to an improved method and apparatus for mining kieselguhr or other diatomaceous earths contained in natural deposits, preferably in the strata formation, whereby the expense of removing the overburden overlying successive strata is overcome and the desired material is worked by the employment of a mechanism which tunnels inwardly at an angle to the face of the vein. The invention further consists in an apparatus whereby 35 the material is reduced to a relatively fine condition, is collected, its bulk is reduced by its being further ground and dried and compressed into predetermined shapes or forms whereby the compressed material is 40 delivered from the tunnel formed by the apparatus in a comparatively small compass, thereby eliminating the loss of the fine material and dust which takes place with the present form of mining or block cutting. 45 Another object of the invention is in the provision of an improved form of cutter head and material lifting bucket mechanism designed for rotary movement and associated with driving mechanism suitably 50 guided, and with which mechanism is carried drying means in which the cut material

is deposited, crushing means through which the dried material passes and briquette forming mechanism for compressing the material into suitable articles, the various mechanisms being movable as a unit into the tunnel formed by the cutter head. 55

A further object is to provide a face cutting implement carrying on one face devices for cutting material and for transferring 60 the same to the rear of the implement, and to provide in connection with the implement elevating and conveying means for moving the transferred material rearwardly in the tunnel; another object consists in a mechanism 65 designed for reducing to a comparatively fine condition the material excavated, and at the same time provides a tunnel for the reception of the tunneling machine, thereby overcoming the necessity of removing the overburden which occurs in deposits 70 of this kind.

With the above mentioned and other objects in view, the invention consists in the novel construction and combination of parts 75 hereinabove described, illustrated in the accompanying drawings, and set forth in the claims hereto appended, it being understood that various changes in the form, proportion, size and minor details of construction within 80 the scope of the claims may be resorted to without departing from the spirit or sacrificing any of the advantages of the invention.

To more fully comprehend the invention, 85 reference is directed to one embodiment thereof wherein:

Fig. 1 is a longitudinal sectional view of a portion of the apparatus.

Fig. 1^a is a longitudinal sectional view 90 of the remaining portion thereof.

Fig. 2 is a sectional view taken on line 2—2 of Fig. 1 illustrating more particularly the guide mechanism of the primary and secondary carriages. 95

Fig. 3 is a view in elevation of the means for retaining the main frame in locked position within the tunnel.

Fig. 4 is a view in transverse detail of the supporting truck between the main and 100 secondary frames.

Fig. 5 is a view in detail of the worm and

pinion adjusting mechanism between the main and secondary frames.

Fig. 6 is a view in transverse detail of a pair of the briquette molds with their plungers in their innermost position.

Fig. 7 is a view similar to Fig. 6 with the plungers in material compressing position.

Fig. 8 is a view in transverse detail taken on line 8—8 illustrating the worm and conveyor and material drying means.

Fig. 9 is a transverse sectional view of the conveyor and worm crushing rolls.

Fig. 10 is a view in elevation of a pair of the formed briquettes.

Fig. 11 is a view in elevation of the face cutting implement illustrating the spider, the ring, the cutting members, and the curved elevating arms.

Fig. 12 is a detail in elevation of a pair of the cutting chisels mounted in their supporting block.

Fig. 13 is a view in end elevation of the chisel supporting block illustrated in Fig. 12.

Fig. 14 is a view in detailed elevation of one of the material elevating buckets on the rear face of the cutting implement, and

Fig. 15 is a view in elevation of the face of a bank illustrating the layer deposits of kieselguhr separated by the non-useable material and illustrating the formation of tunnels by the employment of my improved apparatus.

Referring to the drawings wherein like characters of reference designate corresponding parts in the several views, 1 indicates a pair of track rails of the usual parallel type on which are mounted for longitudinal movement the main carriage 2 and secondary carriage 2', the former being provided with duplicate pairs of supporting wheels 3 and the latter mounting pairs of supporting wheels 4 for engaging the tracks 1 in rear of the point of engagement there-

with by the wheels 3. The main carriage 2 consists in a pair of substantially rectangular open frames 5 united by the horizontal timbers 6, the inner faces of which lie in spaced relation to each other to afford a passage 7 extending from end to end of the carriage 2. The timbers 6 are disposed slightly below the under surface of the upper trans-

verse members of the rectangular open frames 5 as in Fig. 2 of the drawings. This main frame, when within the tunnel, is adapted to be held from longitudinal movement, and a three point locking mechanism is illustrated in the embodiment set forth of the invention, which consists of a jackscrew member 8 threaded into a casting 9 resting on the upper transverse member of the rear frame 5, the upper portion of the jackscrew member carrying a tunnel roof engaging block 10. Associated with the transverse upper member of the forward frame 5 is a

flanged frame 11, to the ends of which are secured the lower ends of toggle links 12, Fig. 3. The link connecting portions of the toggles carry threaded swivel members 13 having threaded connection with the respective ends of the threaded shaft 14 as at 15, the shaft being rotatably held centrally in a bearing 16 resting on the flange 11. The free ends of the toggles 12 are connected by arms 17 hinged together as at 18, and on said arms above the toggles are mounted tunnel roof engaging blocks 19. The rotation of the handle 20 on the shaft 14 will enable the application of great power to the toggle links 12 to force the blocks 19 against the roof of the tunnel and with block 10 to lock the main carriage within the tunnel between the roof and the rails 1. The upper transverse members of the frames 5 are connected by a longitudinal plate 21, Figs. 1 and 4, on which are mounted rails 22 that rest the wheels of a carriage of an auxiliary frame hereinafter described.

The secondary carriage 2' includes a pair of base members 23 slideable over the lower transverse members of the frames 5, as in Figs. 1 and 2 of the drawings, and in parallel spaced relation above said base members are the parallel frame members 24 slideable on the horizontal guide timbers 6. Braces 25 unite the forward ends of base members 23 with the members 24 and rectangular frame members 26 unite the rear ends of base members 23 with the rear ends of the members 24, the members 24 extending outwardly from the upper terminal ends of the members 26, as in Fig. 1 of the drawing. An auxiliary frame member 27 extends longitudinally of the space 7 between the members 6 and parallel with the members 24, as in Figs. 1 and 2, the forward end of the same passing between the members 25. Thus it will be observed that the members 24, 27 and 23 provide a frame projecting forwardly from the secondary carriage and sliding longitudinally through an opening in the main carriage. To steady the secondary carriage frame, there is mounted on a truss 28 connecting with the forward ends of the members 24 and with the frames 26 at the rear a wheeled truck 29, operating on rails 22.

A motor 30 or other suitable source of power is carried by the base members 23 in rear of the main carriage 2 and the same connects through gearing 31 with the cutter shaft 32 rotatable in bearings 33 carried by the frame of the secondary carriage 2'. The shaft 32 is disposed at its outer end at a slight upward inclination, and on said outer end is mounted a spider 34, Fig. 11, and, on the latter in turn is mounted a ring 35 secured to the terminal ends of the spider 34. The spider and ring, with the elements hereinafter described, provide a face cutting

implement, which is inclined upwardly and rearwardly as in Fig. 1 of the drawing. Throughout the area of its outer face, on the ring 35 is mounted tool blocks 36 in each of which are detachably secured one or more face cutting bits or chisels 37, said chisels being detachably secured in place by retaining screws 38. Secured to the outer face of the ring 35 and extending inwardly with their inner terminal ends all curved in the same direction, are a plurality of material carriers or impellers and cutter supporting members 39, on the forward faces of which are mounted blocks 36 and cutters 37. The members 39, it will be observed, extend in a curved path across the portions between the spider arms 34, and in this manner, due to their projecting outwardly from the face of the ring 35 and the outer face of the spiders, are well adapted to impel and guide material toward the openings 40 between the spider arms 34. On the rear face of the ring 35 and near its periphery are mounted the elevating pockets or buckets 41 triangular in elevation and each provided with an opening as at 42 at the side in the direction of the rotation of the ring. The pockets are of sufficient size and number to remove from the floor of the tunnel such material as escapes from the members 39 and is deposited in rear of the ring 35. The cutter head in its cutting operation is disposed at an inclination, Fig. 1, and will in its rotation lie flat against the end of the face of the bore being tunneled with the bits or chisels 37 cutting their way, and their mounting blocks 36 doing likewise where they contact with the tunnel face. The rotation of spider 34 and ring 35 with their attendant cutting elements will, due to the lack of space between the ring and spider faces and the tunnel face, cause an upward movement of the tunneled material as the same is cut, or which may have been previously cut and dropped by gravity to the base of the tunnel. On the elevated material arriving at a point above the horizontal it will slide from whatever element elevated it, drop between the spider arms 34 and members 39 to the rear of the cutter head, where it is picked up by the pockets 42, and again elevated and deposited on the belt conveyer 43.

To receive the material as it is dumped from the pockets and from the members 39 and to convey it rearwardly in the tunnel I employ an endless belt conveyer 43 operating on rollers 44 and 44', one disposed transversely of the free end of the projecting frame at one side of the end of shaft 32 and the other carried by a bracket secured to the rear portion of frame 26. A power belt 45 operates over a pulley on the shaft of pulley 44 and drives the same in the direction of the arrow, Fig. 1, the power belt

being driven from a shaft 46. The mined material discharges from belt 43 into a trough 47 on which is mounted a spiral conveyer 47' driven by any suitable mechanism, and the material while being conveyed thus 70 and at the same time agitated in said trough is subjected to the temperature of heating elements 48 disposed longitudinally of the underside of the trough, the elements being heated preferably by electricity. During 75 this time the moisture contained in the mined material is driven off to a considerable extent and the material at this point is in a relatively dry state. To enable this relatively dry material to be economically 80 handled and delivered to the entrance of the tunnel and points of transportation therebeyond with little loss it discharges from opening 48' in trough 47 between the pair of crushing rolls 50 mounted in the casing 51 85 and from which casing leads a discharge spout 52 through which passes the material after being crushed by the rollers 50.

The spout 52 communicates with the hopper 53 of a briquette or block forming apparatus preferably of the type illustrated in United States Letters Patent No. 811,860 granted to me on February 6th, 1906. This apparatus may be readily understood from the following brief description, but a more 95 detailed description is set forth in the Letters Patent above referred to.

The apparatus consists primarily of a plurality of independent molds 54 slidably mounted with their side walls abutting within an oval frame illustrated in dotted lines in Fig. 1^a as at 55, the frame being carried by the rear end of the secondary carriage 2'. Within the mold chamber 56 of the respective molds is reciprocably mounted 100 a compressing plunger 57, the stem of which mounts a roller 59. Externally of the frame 55 are positioned plunger operating guide rails 60 and 61, the rail 60 being disposed at one end of the oval frame to cause a withdrawal of the plungers 57 in their respective mold chambers and the rails 61 being disposed parallel with the lower side of the bottom portion of the oval frame to limit the outward movement of the plungers 57 in 110 their respective molding chambers. The molds in their movement are disposed with the open ends of the chambers facing inwardly and the stems of the plungers being outwardly disposed, and at one end of their 120 path of travel the inner faces of successive molds contact with successive flat surfaces 62 of a rotating anvil 63 polygonal in transverse section. In their path of travel over the guide rail 61, when in inverted position, the molds 54 afford a bottom for the hopper 53 and the material heretofore dried and ground and maintained under agitation within the hopper 53 by the agitator 64 fills 125 the respective chambers 56, and is pressed 130

therein as the chambers pass beneath the compressing roll 65 at one end of the hopper. In their travel the ends of the molds successively contact with the flat faces 62, and 5 as the anvil 63 revolves they push one another forwardly in the direction of the arrow 66 until the ends of the plungers 57 pass in timed relation beneath the notches 67 in the periphery of a compressing disk 68 10 carried by a shaft 69, which also mounts a gear 70. The gear 70 is driven in the direction of the arrow by a pinion 71 operated from any suitable source of power. It will be observed that it is the engagement of the 15 ends of the plungers of successive molds with the peripheral recesses 67 of the disk 68 that imparts a travel in a close path to the series of molds, and the action of the inward movement of the plungers 57 is to 20 compress the material within the chambers 56 thereof against the flat face of the polygonal anvil 63. As the series of molds continue on their course they pass beneath an expelling roller 72 driven by a shaft 73, 25 which roller causes a complete inward movement of the plungers at a time when the ends of the chambers thereof are unobstructed, this latter action discharging the compressed briquettes *a* from the respective 30 mold chambers. The briquettes are conveyed from the machine in any suitable manner, an endless belt 74 being shown to receive them from the open ends of the mold chambers 56.

35 By the construction described, it will be apparent that I am enabled to form within a stratified deposit of diatomaceous earth, successive parallel tunnels *b* without removing the overburden between the successive 40 layers of desired material, and in this manner am enabled to deliver from the tunnel entrance the mined material in compressed form either as individual briquettes, or the briquettes in stacked or bundled formation. By the improved cutter, the material is reduced to a relatively fine condition, in which condition it is easily handled.

By mounting the power mechanism, cutting mechanism, drying, crushing and briquette forming mechanism on a single carriage and steadyng the cutting implement by adjustably passing the same through another carriage held in position, I am enabled to drive a tunnel with considerable speed in that as the cutter advances the carriage mounting all of the inter-related mechanism advances therewith, and in using my invention it will be understood that the main and secondary carriages are alternately advanced, the main carriage being advanced toward the tunnel end and the

auxiliary carriage gradually approaching the main carriage as the tunnel is driven.

Having thus described my invention what I claim and desire to protect by Letters Patent of the United States is:—

1. A tunneling mechanism including wheeled main and secondary carriages, the latter in rear of the former and provided with a frame longitudinally movable through and guidably mounted within the former to extend beyond the same, a rotatable face cutter and cut material elevating member at the free end of the frame, means mounted on the secondary carriage for rotating the cutter, a material conveyer on the secondary carriage extending rearwardly from the member for receiving cut and elevated material therefrom, means for operating the conveyer, means for releasably retaining the main carriage in position within a tunnel, and means for advancing the secondary carriage relatively to the main carriage and for retaining the secondary carriage in its adjusted position. 85

2. A tunneling machine comprising a main carriage adapted to be anchored to the walls of the tunnel, a secondary carriage having its forward end projecting through and supported by said main carriage, a cutter head carried by said secondary carriage and projecting forwardly in advance of said main carriage, means for conveying the excavated material rearwardly from said cutter head, and material treating means carried by the rear portion of said secondary carriage and receiving the mined material from said conveying means, and means for driving said cutter head and advancing said secondary carriage relative to said main carriage. 95 100

3. A tunneling machine comprising a main carriage having a wheeled support and adapted to be anchored to the walls of the tunnel, a secondary carriage having a wheeled support and having its forward end only projecting through and supported by said main carriage, a cutter head carried by said secondary carriage and projecting forwardly in advance of said main carriage, means for conveying the excavated material rearwardly from said cutter head, and material crushing and briquetting means carried by the rear portion of said secondary carriage and receiving the mined material from said conveying means, and means carried by said secondary carriage for driving said cutter head and advancing said secondary carriage relative to said main carriage. 110 115

In testimony whereof I have signed my name to this specification.

HOWARD E. MARSH.
